[54] COMBINED LOUVER CLIP AND RETAINER THEREFOR

3,183,561 5/1965 Spicer 49/403
3,903,649 9/1975 Dalia 49/403

[76] Inventor: Salvatore A. Dalia, 2125 W. 234 St.,
Torrance, Calif. 90501

Primary Examiner—B. J. Bullock
Attorney, Agent, or Firm—Howard L. Johnson

[**] Term: 14 Years

[57] CLAIM

[21] Appl. No.: 70,913

The ornamental design for a combined louver clip and
retainer therefor, substantially as shown and described.

[22] Filed: Aug. 29, 1979

DESCRIPTION

[51] Int. Cl. ..... D8—08
[52] U.S. Cl. D8/395; D8/382
[58] Field of Search D8/354, 384, 394, 395,
D8/382; 49/403; 24/255 R, 265 A, 259 R

FIG. 1 is a front elevational view of the combined louver
clip and retainer therefor showing my new design;
FIG. 2 is a bottom plan view thereof;
FIG. 3 is a rear elevational view thereof;
FIG. 4 is a top plan view thereof;
FIG. 5 is an enlarged end elevational view taken in the
direction of the arrows on line 5—5 of FIG. 2;
FIG. 6 is an enlarged end elevational view taken in the
direction of the arrows on line 6—6 of FIG. 2;
FIG. 7 is a reduced perspective view thereof, the portions
of a louver panel and bracket being shown in
broken lines for illustrative purposes only.
